United States Patent Office

Des. 228,739
Patented Oct. 23, 1973

228,739

STUD ANCHOR

Gerald L. Kitson, 9709 Belding Road,
Rockford, Mich. 49341

Filed May 5, 1971, Ser. No. 140,351

Term of patent 14 years

Int. Cl. D8—08

U.S. Cl. D8—235

FIG. 1 is a top plan view of a stud anchor embodying my new design.

FIG. 2 is a side elevation of the stud anchor shown in FIG. 1.

FIG. 3 is an end view of the stud anchor shown in FIG. 1 and FIG. 2.

FIGS. 4 and 5 are perspective views of the stud anchors shown in FIGS. 1, 2, and 3.

The brokering line showings in FIG. 4 and in FIG. 5 are included to illustrate the environment.

I claim:

The ornamental design for a stud anchor, as shown and described.
